Primary Examiner — Patricia Palasik

(74) Attorney, Agent, or Firm — Fish & Richardson P.C.

(57) **CLAIM**

The ornamental design for a machine cover, substantially as shown and described.

DESCRIPTION

FIG. 1 is a perspective view of our design.

FIG. 2 is a front view of our design.

FIG. 3 is a rear view of our design.

FIG. 4 is a left side view of our design.

FIG. 5 is a right side view of our design.

FIG. 6 is a top view of our design; and,
FIG. 7 is a bottom view of our design.

The broken (dash) lines illustrate graphical environmental features that form no part of the claimed design. The broken (dot-dash) lines illustrate boundaries of the claimed design.

1 Claim, 4 Drawing SheetsFIG. 1

FIG. 2

FIG. 3

FIG. 4

FIG. 5

FIG. 6

FIG. 7
